tively secured to the bushing 11 through the medium of a set screw, or other suitable fastening element 28. Spring 19 will have a tendency to cause the roller 10 to rotate in a direction for winding the cable 25 thereon. Thus it will be seen that as the window sash 8a is caused to move downwardly, the roller 10 will rotate about the shaft 15 as an axis in a direction opposing the action of the spring 19 thus permitting the cable 25 to pay out and consequently the lowering of the sash 8a.

It will also be apparent that upon initiating upward sliding movement of the sash 8a, the tendency of the spring 19 to cause the roller 10 to rotate in a direction for causing the cable 25 to wind on said roller will assist upward movement of the sash so that this sliding movement up and down of the sash will be accomplished easily and smoothly.

To tighten the spring 19 the bushing 12 is rotated relative to the roller 10 by inserting a pair of any suitable instruments in selected openings 22 in the bushing in order to cause a step-by-step rotation of the bushing in a direction to wind or tighten up the spring 19. When the spring 19 has been placed at the sufficient tension, one end of the pin 23 is inserted in a selected opening 22 and the outer end of the pin will then abut the body plate of the bracket 6 as shown in Figure 4 to prevent rotation of the bushing 12 in a direction as would permit quick, or too-rapid unwinding of the spring.

It is thought that a clear understanding of the construction, utility and advantages of a sash

balance embodying the features of the present invention will be had without a more detailed description thereof.

It is also to be understood that while I have herein illustrated and described the preferred embodiment of the invention, it is in no wise intended to restrict the invention to the precise details of construction, combination and arrangement of elements, other than may be required by the prior art and scope of the claim hereunto appended.

Having thus described the invention what is claimed as new is:

A sash balance for a window comprising a bracket adapted to be attached to the window frame at the top thereof, a shaft rigidly fixed to the bracket, a cable winding cylinder rotatably mounted at one end on the shaft, a cylinder tensioning spring coiled around said shaft within said cylinder and operatively connected to the cylinder to rotate the same and wind said cable, and means to variably tension said spring comprising a bushing on said shaft extending part way into the other end of the cylinder to rotatably mount said end, said bushing being rotatable on said shaft and embodying radial circumferentially spaced bores for insertion of an instrument therein selectively to rotate the bushing in a direction opposing the spring, and a pin for insertion in said bores selectively and co-acting with said bracket to block rotation of the bushing in the opposite direction.

HAROLD J. BELCHER.
